UNITED STATES PATENT OFFICE.

RICHARD LABORDA, OF SAN FRANCISCO, CALIFORNIA, ASSIGNOR OF ONE-HALF TO
JOHN D. SPRECKLES, JR., OF SAN FRANCISCO, CALIFORNIA.

SUGAR PACKING AND BOXING MACHINE.

1,367,821.

Specification of Letters Patent.

Patented Feb. 8, 1921.

Application filed March 30, 1920. Serial No. 369,926.

To all whom it may concern:

Be it known that I, RICHARD LABORDA, a subject of the King of Spain, residing at San Francisco, in the county of San Francisco and State of California, have invented certain new and useful Improvements in Sugar Packing and Boxing Machines, of which the following is a specification.

This invention relates to certain new and useful improvements in a sugar packing and boxing machine and more particularly to improvements on the construction shown in application Serial No. 294,806 and filed May 5, 1919, by me as joint inventor with J. D. Spreckels, Jr.

The invention has for its objects to provide means to facilitate the stacking of the cubes of sugar in assembled form; improved means for supporting and transferring the assembled cubes to a receiving platform; other improved means for separating the stacked cubes into predetermined numbers or quantities for subsequent packing containers; and means for filling or 25 packing the containers with the sugar content in an improved and efficient manner.

The invention further resides in an improved machine which will be efficient and thoroughly reliable in operation and by 30 which the sugar can be packed in their containers very expeditiously and with a minimum of handling.

It consists in the features of constructions and the arrangements and combinations of parts hereinafter described in detail and claimed succinctly, reference being had to the accompanying drawings wherein:

Figure 1 is a fragmental top plan view of the improved machine;

Fig. 2 is an end elevation thereof viewing the same from the left in Fig. 1;

Fig. 3 is a front side elevation of the machine as depicted in Fig. 1;

Fig. 4 is a longitudinal section on line 4-4 of Fig. 1 showing more clearly the means for filling the cartons or boxes with sugar;

Fig. 5 is an end elevation of the machine as viewed from the right in Fig. 1 and depicting the manner of assembling and stacking the sugar cubes; and

Fig. 6 is a detailed perspective of one of the sugar-assembling racks.

Referring more in detail to the drawings, 55 the numeral 1 designates the main frame or

supporting table which is provided in its longitudinal, side top frame members 2 with journal bearings for rotatably supporting the rollers 3 whereby the stacking platforms or trays, 4 can expeditiously and easily be shifted from the assembling end 5, of the machine, to the opposite end where the stacked cubes are divided into groups of a predetermined size and fed or inserted into the empty cartons or other containers. 60

The assembling or stacking platform comprises a flat plate or body having an upstanding front wall 6, which is equipped with a handle 7 to facilitate moving the platform along the roller top of the main frame, and a pair of upstanding stops or posts 8 spaced along its rear side edge to normally support the removable side wall 9 in its operative position. 70

When the sugar is deposited upon the 75 platform 4, from the drying trays 13 the cubes are relatively spaced and require being moved close together or assembled. This is accomplished by means of a right angular rack 10 which has one arm placed 80 across the platform and the other arm extending and supported alongside the latter by a raised ledge and guide 12^a, as disclosed in Fig. 5, the platform having initially been set to engage the stops 12 disposed at the 85 extreme end of the table. In practice, a tray 13, with the cubes of sugar thereon, is placed on the movable platform and the tablets or cubes are then assembled. After assembling them by means of a rack 10 a 90 second tray with its cubes are placed on the first layer and so on until the desired number of layers have been stacked. The trays 13 are then withdrawn, and in order to retain the underlying layers intact, during 95 such withdrawal a stop 14 is pivoted to the end of the table for being swung upwardly across the underlying assembling racks to prevent their accidental displacement.

As soon as the operator has filled or 100 stacked one platform the latter is shifted along the table ready for replacing an empty platform, said table being sufficiently long to accommodate several platforms.

The operator at the left or carton-filling 105 end of the machine pulls the fresh platform against a pair of stops 15 which position the same relative to the transfer and dividing platform 16. This latter is movable from the main structure, being supported on 110

the upper end of a weighted lever 17 that is pivoted intermediately on a bracket 18 mounted on the horizontal frame member 19 of the main frame. A pedal or foot lever 20 is also pivoted to the frame and linked to the lower, weighted end of the lever 17 whereby, upon pressing down on the foot lever, the operator is enabled to hold the platform 16 firmly against the table and 10 platform 4 during the transfer of the stack from the latter platform to the former. Normally the weighted lever or arm 17 serves to hold the empty platform 16 against the table but when a stack of sugar is moved 15 over onto said platform the latter will be overbalanced and would move from the table were it not for the pressure of the foot on pedal 20.

The tablets or cubes of sugar are packed 20 both lengthwise and crosswise according to the varying tastes of the different communities. Also the different sized containers or cartons will require corresponding greater or lesser rows of sugar cubes to fill them. 25 Therefore, to expedite the transfer of the required number of cubes certain gage means are provided, consisting of an adjustable wall 21 connected by a toggle leverage 22 to a fixed bracket 23, and a pair of gage stops 30 24 designed to limit the retrograde movement of the wall 21. These stops are removable and replaceable by others when a different number of rows of cubes are to be received on the tilting platform 16.

35 The functioning and operation of this gaging device is as follows: The movable wall 21 is advanced to the stacked platform and then, by means of pusher bar 25 supported on the opposite side of the table in a bearing bracket 26 for sliding transversely of said table, the side wall 9 is caused to shove the stack of cubes, row after row, off onto the platform 16 which progressive movement pushes back the wall 21 until limited by engagement with the stops 24. An overhanging handle 27 is carried by pusher bar to facilitate operating the same. In the present construction the tablets of sugar are laid lengthwise across the stacking platform or 40 transversely of the table, there being fifteen tablets across, twenty-eight deep in each layer and eight deep in the stack. Thus it may happen that one or more rows will be left over in the stack after removing the several equal 45 divisions required for the predetermined size cartons. When there is a remainder thus left over, which will not move the wall 21 back against the gage stops, said wall is retained against the remaining rows of 50 cubes, which have been moved onto platform 16, by tightening the pivotal connection between the toggle levers through the instrumentality of wing nut 28. Thereafter, a fresh platform of cubes is substituted for 55 the emptied one and the remainder from the

preceding stack supplemented by the fresh stack to provide the required quantity, the wing nut 28 having first been released.

Detachably mounted on the delivery end 70 of platform 16 is a carton-holder 29 the same being connected to the platform by the bolts 30 and consisting of a plate 31 and a right-angularly sectioned trough 32 fixed to and extending from said plate. This trough has a side wall with which the adjustable wall 75 of platform 16 aligns, and when other gage stops are employed a corresponding trough is also substituted.

The transfer platform 16 is provided with 80 a lengthwise slot 33 through which the shank 34 of a follower 35 operates, the lower end of the follower shank having apertures therethrough to guidingly receive the rigid horizontal rods 36 disposed beneath the platform. Also beneath the platform is an end- 85 less chain or cable 37 which is supported for movement lengthwise of the slot by the sprockets or pulleys 38, the idler pulley being journaled in brackets 39 on the plate 31, for which reasons a slot 40 is cut in said plate, and the drive pulley being fixed on a shaft 41 which is journaled in bearings 42. This cable is fixedly connected to the follower base whereby upon travel of the cable the follower will also be moved to advance the sugar tablets across the guide trough 32 and into the carton, the latter being slipped over the outer end of the trough. 90 As the follower continues its movement the tablets are forced, with the carton, off the 100 end of the trough and another carton is placed thereover.

The movement of the follower is intermittent, being actuated by lever 43 which is pivoted on the projecting end of shaft 41 105 and equipped with a spring pressed pawl 44 normally held in engagement with a ratchet 45 fixed on the shaft. The operating lever is weighted to stand normally erect in which position the pawl is automatically lifted 110 from the ratchet by engagement with a trip 46, whereby the follower will be free for manual shifting. A series of openings 47 in the adjacent side of the tilting platform are designed to selectively receive a stop pin 48 with which the lever contacts and is thereby limited to rotate the ratchet a pre-determinable degree. Thus, this gaging means determines the number of transverse rows to be inserted in a carton while the 120 gage stops on the platform determine the number of longitudinal rows.

It is believed the operation will be clear 125 from the foregoing detailed description, the stack being moved from the assembling platform onto the transferring platform which is then tilted to separate or divide the stack. The follower is then advanced to shift the separated portion lengthwise between the side wall of the trough and an upstanding 130

rubber roller 49 which urges the tablets into a compact body just prior to entering the carton. The pressure roller 49 is journaled on an offset bracket 50 secured to the plate 5 31 of the carton holder.

The construction is very simple, easy of operation and efficient and practical throughout. The cartons are quickly filled, one swing of the lever advancing sufficient tablets to supply one container. The follower 10 facing 51 is also replaceable by another of smaller or larger dimensions according to the working surface of the transfer platform, said facing projecting sufficiently far 15 to clear the end frame member of said platform to which the carton holder is secured.

What is claimed is:

1. A sugar packing and boxing machine comprising a main structure, a platform 20 thereon on which the sugar tablets are assembled and stacked, means for shifting the stacked tablets from the platform, a transfer platform mounted for movement toward and from the first platform for receiving tablets therefrom, a carton holding device at the discharge end of the transfer platform over which a carton is adapted to be slipped, a follower movable along the transfer platform, and means for intermittently moving the follower.

2. In a device of the character described a main frame, a platform thereon upon which cube sugar is adapted to be assembled and stacked in superposed layers, a transfer platform supported by the main frame, means for transferring sugar from the first named platform to the transferring platform, means permitting movement of the transferring platform with relation to the main frame and the first named platform to separate the sugar delivered thereto with relation to the main body of sugar supported by the first named platform, and means for transferring the sugar delivered 45 to the transferring platform into successive cartons.

3. A sugar packing and boxing machine comprising a main structure, a platform thereon on which the sugar tablets are assembled and stacked, means for shifting the stacked tablets from the platform, a transfer platform mounted for movement toward and from the first platform for receiving tablets therefrom, a carton holding device 50 at the discharge end of the transfer platform over which a carton is adapted to be slipped, a follower movable along the transfer platform and engageable with the sugar, and means for actuating the follower, said 55 last means including a lever and means for adjusting the swing thereof to accord the follower predetermined movements.

4. In a device of the character described a main frame, a platform thereon upon 60 which cube sugar is adapted to be assembled

and stacked in superposed layers, a transfer platform supported by the main frame and movable to and away from said frame, a follower slidably mounted on the first named platform engageable with the stacked sugar 70 and movable to transfer the sugar to the transfer platform, a carton holding device on one end of the transfer platform, and a slidably mounted follower on the transfer platform engageable with the sugar transferred thereto and movable to transfer the sugar into cartons.

5. In a device of the character described a main frame, a platform thereon upon which cube sugar is adapted to be assembled 80 and stacked in superposed layers, a transfer platform supported by the main frame and movable to and away from said frame, a longitudinally extending guide plate on said platform, means for adjusting the position 85 of said guide plate, a follower carried by the first named platform and slidable thereon, said follower adapted to engage the stacked sugar on the platform and to transfer it to the transfer platform, and a slidably mounted follower on the transfer platform engageable with the sugar transferred thereto and movable to push the sugar longitudinally of the platform along the guide plate mounted thereon, and a carton holding 90 device on the end of the transfer platform adapted to receive the sugar thus moved.

6. In a device of the character described a main frame, a platform thereon upon which cube sugar is adapted to be assembled 100 and stacked in superposed layers, a transfer platform supported by the main frame, a follower slidably mounted on the first named platform and engageable with the stacked sugar to transfer the sugar to the transfer 105 platform, means permitting movement of the transfer platform with relation to the main frame to separate the sugar delivered thereto with relation to the sugar supported on the first named platform, a carton holding device at one end of the transfer platform and a slidably mounted follower on the transfer platform engageable with the sugar supported thereby and movable to transfer the sugar into successive cartons.

7. In a device of the character described a main frame, a platform thereon upon which cube sugar is adapted to be assembled and stacked in superposed layers, a transfer platform supported by the main frame, a follower slidably mounted on the first named platform and engageable with the stacked sugar to transfer the sugar to the transfer platform, means permitting movement of the transfer platform with relation to the main frame to separate the sugar delivered thereto with relation to the sugar supported on the first named platform, a longitudinally extending guide plate on the transfer platform, means for permitting lateral ad- 115 120 125 130

justment of the same to determine the number of columns of sugar which may be received by the transfer platform, and means for imparting longitudinal movement to 5 the sugar transferred to the receiving platform.

8. In a device of the character described the combination with a platform upon which cube sugar is adapted to be assembled

10 and stacked in superposed layers, of a transfer platform supported adjacent the same, means on the first named platform for transferring sugar to the transferring platform, means permitting tilting movement of the 15 transferring platform with relation to the first named platform to separate the sugar delivered to the transferring platform with relation to the sugar supported by the first named platform, a carton holding device on 20 one end of the transfer platform, and means for imparting longitudinal movement to the sugar supported by the transfer platform to transfer the sugar into cartons.

9. In a device of the character described 25 a main frame, a platform thereon upon which cube sugar is adapted to be assembled and stacked in superposed layers, a trans-

fer platform supported by the main frame and movable to and away from said frame, means permitting endwise movement of the 30 first named platform upon the main frame to position it in alignment with the transfer platform, and means slidably mounted, on the first named platform for transferring assembled columns of sugar to the transfer 35 platform.

10. In a device of the character described a main frame, a platform thereon upon which cube sugar is adapted to be assembled and stacked in superposed layers, a transfer 40 platform supported by the main frame and movable to and away from said frame, means permitting endwise movement of the first named platform upon the main frame to position it in alignment with the transfer platform, a follower slidably mounted on the first named platform for transferring assembled columns of sugar to the transfer platform, and an adjustable guide 45 plate on the transfer platform by which 50 the number of columns of stacked sugar transferred may be regulated.

In testimony whereof I affix my signature.
RICHARD LABORDA.
